COIL TERMINAL

Luther E. Sevison, Toledo, Ohio, assignor to The
Machined Parts Corporation, Detroit, Mich., a
corporation of Michigan

Application June 25, 1934, Serial No. 732,281

4 Claims. (Cl. 175—357)

This invention relates to insulating caps such as used on ignition coils and similar electrical ignition apparatus, and it is the prime object of the invention to provide a cap of insulating material so designed and constructed that the distance or gap between the secondary terminal and the primary terminals is materially lengthened; consequently, any possibility or tendency of the secondary current to "short" to one of the primary terminals is minimized or entirely eliminated.

Another object is to provide a cap and terminal assembly which insures a positive connection at all times, which eliminates the usual metal inserts found in conventional sockets and terminals, thereby simplifying the manufacturing and reducing the production cost.

A further object is to provide simple and economical means for forming an electrical connection between the secondary lead and the high tension cable, as well as means for clamping the end of the high tension cable in the terminal socket.

A still further object is to provide means for positively sealing the coil cap to eliminate the possibility of moisture, dust or other foreign matter entering the secondary terminal or terminal socket.

With the above and other objects in view the present invention consists in the combination and arrangement of parts, hereinafter more fully described, illustrated in the accompanying drawing, and particularly pointed out in the appended claims, it being understood that changes may be made in the form, size, proportion, and minor details of construction, without departing from the spirit or sacrificing any of the advantages of the invention.

In the drawing—
40 Fig. 1 is a part sectional side elevation of an ignition coil showing my cap in connection therewith.

Fig. 2 is a top plan view.
45 Fig. 3 is a vertical sectional view of the terminal, illustrating the manner of connecting the high tension cable with the secondary lead.

Fig. 4 is a plan thereof.
50 In the conventional ignition coil, a brass insert or ferrule is moulded into the center or secondary terminal socket, and as this insert is from one-half to one inch long, the path of the electrical current between the secondary and primary terminals is shortened accordingly. Moisture gathering in the inside of the secondary terminal 55 socket, and grease laden with dust or carbon

deposits accumulating on the outside of the cap, causes the secondary current to seek a path up and around the neck of the secondary terminal socket and to "short" across to one of the primary terminals, and I have, therefore, designed 5 a cap which is moulded, preferably of bakelite, or other plastic material of high dielectric strength, and in which all metal inserts in the secondary circuit are eliminated, thereby increasing the distance or path of the electrical current between 10 the secondary and primary terminals, and providing for a more efficient operation and economical construction.

Referring now more particularly to the drawing, the numeral 5 indicates a cylindrical metal 15 tube or shell which can be formed in any desired manner, and a bakelite cap 6 forms a closure for the open upper end thereof, a groove 7 being moulded in said cap, and the upper end of the shell is beaded and pressed into said groove for 20 rigidly securing the cap thereto.

The cap 6 is formed as clearly shown in Figs. 1 and 2 of the drawing, the projecting neck 8 of the cap having a slightly tapered cored socket 9, internally threaded as at 10 to receive the secondary terminal 11, said socket terminating in a 25 reduced passage 12 which opens to the downwardly extending tubular extension 13 which is moulded integral with the cap.

Bosses 14 are moulded on the cap in spaced 30 apart relation, and hollow primary terminals 15 are moulded in said bosses, and to which the primary lead wires are adapted to be connected in the usual manner.

The iron wires 16 which form the core portion 35 of the magnetic circuit of the coil project into the tubular cap extension 13 and are encased in a nonconducting insulating tube 17 which is surrounded by the secondary winding 18, said winding comprising a plurality of layers of a large 40 number of turns of fine wire separated by paper insulation, the margin of which is indicated at 19. The primary winding 20 surrounds the secondary winding, and this primary winding is in turn 45 surrounded by outer laminations of magnetic material 21 in the usual manner.

In assembling the coil I first pour wax in the bottom of the coil assembly, after which I turn it end for end and thread the lead wires 22, 23, and 24 into the cap; I then place the assembly in 50 the shell, pour wax in the shell around and over all the coil assembly, thereby sealing it into the shell, press the cap firmly in position, and secure it by rolling the upper edge of the shell 55 into the groove 7 in the cap. These primary

lead wires 22 and 23 can then be soldered or otherwise secured to the terminal screws 15. The secondary lead wire 24 is connected in a different manner, the end section, which extends into the cored socket 9, being crushed or matted down as shown at 25 in Fig. 3, so as to prevent disengagement and to further provide a suitable contact.

The secondary terminal 11 is also moulded and is formed as clearly shown in Fig. 3 of the drawing, the upper end being preferably shouldered and knurled as at 26, the reduced lower end section being tapered and is threaded at a point intermediate its length to engage the threaded section of the cored socket 9 so that it can be firmly secured in position, a rubber washer 27 being interposed between the shoulder on the terminal and the upper end of the neck 8, and forms a tight dust and moistureproof joint.

A centrally disposed tapered passage 28 is provided in the upper end of the terminal 11, said passage opening into a reduced passage 29 which extends through the terminal, and I wish to direct particular attention to the fact that there are no metal inserts or ferrules on this terminal 11 or 25 in the socket 9 in which it is inserted.

The end section 30 of the high tension cable 31 is bared as shown in Fig. 3 of the drawing, and the tapered passage 28 is of predetermined size so that when the high tension cable is inserted, 30 it must be forced and twisted around several times to force it to position, so that the end of the insulation bottoms on the shoulder of said passage. This causes the wall of the cable insulation to become compressed in the passage, and to form a 35 dust and moistureproof seal.

When the high tension cable has been forced to proper position, the bared section 30 will extend downwardly with the end projecting beyond the end of the terminal, the separate strands of this 40 end section being spread to form an electrical connection with the secondary lead wire which is crushed in the bottom of the socket 9, and when the terminal 11 is screwed in the socket 9 of the cap, the end strands of the bared wire 31 are 45 firmly pressed against the crushed end 25 of the secondary lead wire 24, forming a positive electrical connection, said strands being clamped between the bottom of the socket and the end of the terminal, thereby rigidly securing the high 50 tension cable in position, and eliminating the possibility of its being pulled out and breaking the electrical connection.

This construction positively seals the coil cap from the sealed high tension cable insulation 55 joint to the end of the secondary terminal without possibility of moisture, dust, or foreign conducting matter reaching the chamber, the rubber washer 27 sealing the joint between the end of the cap neck 8 and the shoulder on the secondary terminal 11, thus the entire socket 9 is positively sealed with no possibility of moisture or other foreign elements altering the insulating features which have been created.

It will, of course, be understood that the winding, assembly, etc. of the coil is immaterial and

that any desired method may be used, as this invention is directed to the insulating and sealing of the cap, secondary terminal, the connections, and manner of securing.

From the foregoing description it will be obvious that I have perfected a very simple, practical, efficient, and economical cap for ignition coils and similar electrical equipment.

What I claim is:

1. In an ignition coil the combination of an 10 insulating member having a wholly non-conductive, tapered and internally threaded socket therein, a shouldered wholly non-metallic, tapered and threaded secondary terminal adapted for engagement in the socket, a tapered passage 15 in said terminal, a high tension cable adapted to be inserted in said passage to form a dust and moisture-proof seal thereat, and a resilient washer interposed between the top of the insulating member and the shoulder on the terminal to form a dust and moisture-proof seal thereat.

2. In an ignition coil the combination of an 20 insulating cap member having a wholly non-conductive, tapered and internally threaded socket therein and terminating in a reduced passage 25 adapted to accommodate the secondary lead of the coil, a wholly non-metallic, tapered and threaded shouldered secondary terminal adapted for engagement in the socket, and provided with a tapered passage therethrough, a high tension 30 wire adapted to be mounted in said passage and forming a dust and leakproof seal thereat, the end of the wire being bared and projecting beyond the end of the terminal to form a contact with the secondary lead of the coil, and a washer 35 interposed between the upper end of the cap and the shoulder on the secondary terminal to form a leakproof joint thereat.

3. In an ignition coil, the combination of an 40 insulating member having a wholly non-conductive, tapered and internally threaded socket therein, a wholly non-metallic, tapered and externally threaded, shouldered and hollow terminal adapted for engagement in the socket, a high tension wire adapted to be mounted in said 45 terminal, the end of said wire being bared to form a connection with the secondary lead of the coil, and a resilient washer interposed between the top of the insulating member and the shoulder on said terminal.

4. In an ignition coil, the combination of an 50 insulating cap having a wholly non-conductive, tapered and internally threaded socket therein, a wholly non-metallic, tapered and externally threaded terminal adapted for engagement in 55 the socket, and formed with an external shoulder and a shouldered, tapered passage therethrough, a high tension wire mounted in said passage with its bared end projecting beyond the end of said 60 terminal for engagement with the secondary lead of the coil, and a resilient washer interposed between the upper end of the cap and the external shoulder on the terminal to form a tight, leakproof joint thereat.

LUTHER E. SEVISON.
